(57) **CLAIM**

The ornamental design for a wheelchair, as shown and described.

DESCRIPTION

FIG. 1 is a rear, top, and right side perspective view of a wheelchair showing the new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side elevational view thereof.

FIG. 7 is a left side elevational view thereof.

FIG. 8 is an enlarged view of the section indicated by lines 8-8 in FIG. 1.

FIG. 9 is a cross-sectional view thereof, taken along lines 9-9 in FIG. 2; and,

FIG. 10 is an enlarged view of the section indicated by lines 10-10 in FIG. 9.

The broken lines depict portions of the wheelchair that form no part of the claimed design.

1 Claim, 10 Drawing Sheets
